DESIGN FOR A ROOF VENTILATOR

Frederick J. Kreutzer, Fort Atkinson, Wis., assignor to James Manufacturing Company, Fort Atkinson, Wis.

Application April 14, 1938, Serial No. 76,492

Term of patent 14 years

To all whom it may concern:

Be it known that I, Frederick J. Kreutzer, a citizen of the United States, residing at Fort Atkinson, in the county of Jefferson and State of Wisconsin, have invented a new, original, and ornamental Design for Roof Ventilators, of which the following is a specification, reference being had to the accompanying drawing, forming a part thereof.

Figure 1 is a perspective view and Figure 2 is a top plan view of a ventilator showing my new design, the sides not shown in Figure 1 are similar to those shown.

I claim:

The ornamental design for a roof ventilator, as shown and described.

FREDERICK J. KREUTZER.
